UNITED STATES PATENT OFFICE.

ANDREW J. BARRON, OF CINCINNATI, OHIO, ASSIGNOR TO THE CINCINNATI HORSE SHOE & IRON COMPANY, A CORPORATION OF OHIO.

AUTOMOBILE TRUCK CONSTRUCTION.

Application filed August 26, 1922. Serial No. 584,428.

To all whom it may concern:

Be it known that I, ANDREW J. BARRON, residing in Cincinnati, county of Hamilton, State of Ohio, and a citizen of the United States, have invented certain new and useful Improvements in Automobile Truck Constructions, of which the following is a specification.

This invention has for its object the provision of novel structural means for adjustably securing the body sills of Ford trucks on a rear channel-bar.

Some Ford trucks have the body sills placed over the channels of the truck, and this makes them closer together than if they were placed on the flanges intended to support them. Again, there is another form of body with sills of irregular widths. My form of channel-bar, and the sill strap-irons and securing clips (hereinafter particularly described) in co-operative combination with the channel-bar, are adapted for use with any style of Ford truck.

The accompanying drawing illustrates an exemplary form of my invention. Briefly described:

Figure 1 is a top plan view of so much of the rear portion of a Ford truck as is necessary for an understanding of the inventive improvements shown applied thereto;

Figure 2 is a view in end elevation; that is, a view showing my improvements as they appear when viewed from a position at the rear end of the truck; the channel bar being partly broken away;

Figure 3 is a sectional view, on the plane of the line 3—3, Fig. 1, looking in the direction of the arrow indicated thereon;

Figure 4 is a detached detail view, in perspective, of one of the clips of my invention.

Referring, now, in detail to the drawing:

1, 1 designate the conventional body-sills of the Ford truck, 2 designates the rear cross spring, 15, 15 side springs, 16, 16 the usual longitudinal members, and 18 the propeller-shaft, which is extended rearward to bring the differential 19 to a position in rear of the usual cross member 20.

3 designates my channel-bar disposed over and extending longitudinally of the spring 2, and secured thereto in appropriate manner, as by means of the threaded bolts 4 passing through the channel-bar and through a plate 5 adapted to bear against

the under surface of the spring 2, nuts 6 being screwed on the threaded ends of the bolts and against the plate 5. Preferably, as shown, the bolts 4 do not pass through the spring 2. The desirable arrangement is as shown in the drawing, wherein it is seen that said bolts are, in the assembled position of the parts, disposed adjacent the spring, at the sides thereof. The channel-bar 3 is disposed, as shown, so that the two side longitudinal flanges thereof project downward, toward the spring 2.

The means for adjustably securing the sills 1, 1 on the channel-bar 3 will now be described. For each sill two strap-irons 7, 7 are provided, each strap-iron having threaded terminals 8, 8. Co-operating with each strap-iron are two clips 9, 9, most clearly shown in Fig. 4. The clips are of peculiar form, and each has a flat face 10 adapted to bear squarely against one of the side flanges of the channel-bar 3, a curved terminal jaw or hook-portion 11 adapted to engage under the said side flange of the channel-bar, and a flange 12 at right-angles 75 to the plane of the surface or wall 10 and on the side of said wall opposite that of the jaw or hook 11, said flange 12 being perforated, as shown at 13 to permit one leg of the strap-iron 7 to project therethrough. 80 Nuts 14 screwed on the threaded ends 8 of the legs of the strap-irons 7 secure the sills 1, 1 in adjusted position.

By loosening or removing the nuts 14, the sills 1, 1 are free to be adjusted relative to the channel-bar 3, either longitudinally or transversely thereof, or, vice versa, the channel-bar 3 may be adjusted relative to the sills 1, 1.

Having thus fully described my invention, 95 what I claim as new and desire to secure by Letters-Patent is:

1. The combination with the body sills of a Ford truck, of a channel-bar upon which said body sills are adapted to rest, 100 said channel-bar being disposed with its two longitudinal side flanges projecting downward, and means including clips bearing against and engaging under said side flanges, for adjustably securing said sills to said 105 channel-bar.

2. The combination with the body sills of a Ford truck, of a channel-bar upon which said body sills are adapted to rest, 110 said channel-bar being disposed with its

two longitudinal side flanges projecting downward, and means for adjustably securing said sills to said channel-bar, comprising clips bearing against and engaging under said side flanges, and members passing over said sills and operatively connected with said clips.

3. The combination with the body sills of a Ford truck, of a channel-bar upon 10 which said body sills are adapted to rest, said channel-bar being disposed with its two longitudinal side flanges projecting downward, and means for adjustably securing said sills to said channel-bar, comprising clips bearing against and engaging 15 under said side flanges, and straps passing over sills and projecting through said clips.

4. The combination with the body sills of a Ford truck, of a channel-bar upon 20 which said body sills are adapted to rest, said channel-bar being disposed with its two longitudinal side flanges projecting downward, and means for adjustably se-

curing said sills to said channel-bar, comprising clips hooking under said side flanges 25 and each clip provided with a perforated flange, and members passing over said sills and projecting through the perforations in the clip-flanges.

5. The combination with the body sills 30 of a Ford truck, of a channel-bar upon which said body sills are adapted to rest, said channel-bar being disposed with its two longitudinal side flanges projecting downward, and means for adjustably securing said sills 35 to said channel-bar, comprising clips each having a lateral hook-portion engaging under one of the said side flanges of the channel-bar, and having, also, a perforated flange, and members passing over said sills 40 and projecting through the perforations in the clip-flanges.

In testimony whereof, I hereunto affix my signature.

ANDREW J. BARRON.
